UNITED STATES PATENT OFFICE.

ALBERT EARL CRANSTON, OF SPOKANE, WASHINGTON.

KNOTTER.

1,388,553.

Specification of Letters Patent. Patented Aug. 23, 1921.

Application filed October 29, 1920. Serial No. 420,519.

To all whom it may concern:

Be it known that I, ALBERT EARL CRANSTON, a citizen of the United States, and a resident of Spokane, in the county of Spokane and State of Washington, have invented certain new and useful Improvements in Knotters, of which the following is a specification.

My invention relates to knotters used for 10 twisting the severed ends of a loop of wire subsequent to the wrapping of a bundle of shingles, staves or the like for securing the same together for shipment, and it contemplates certain new and useful improvements 15 in the knotter embodied in my pending application Serial No. 322,086, filed September 6, 1919.

A purpose of my invention is the provision of a knotter which positively grips the 20 wire ends in advance of the cutting operation thereby eliminating the possibility of the severed wire ends slipping from the knotter during the twisting operation.

It is also a purpose of my invention to 25 provide a knotter including a movable member and a stationary member, the former being formed with a recess of a predetermined depth to accommodate wires of a predetermined gage so that the confronting 30 faces of the two members will securely grip wires during movement of the movable member, thereby eliminating the employment of a gripping lug, and consequently reducing the cost of manufacture of the 35 knotter.

A further purpose of my invention resides in the provision of a knotter having 40 means for allowing the ready withdrawal of the twisted wire ends from the knotter upon completion of the twisting operation, and in such manner as to permit of the wire ends retaining their angular bent positions.

I will describe one form of knotter embodying my invention and will then point 45 out the novel features thereof in claims.

In the accompanying drawings:

Figure 1 is a view showing in top plan one form of knotter embodying my invention.

Fig. 2 is a view similar to Fig. 1 showing the knotter as having been slightly revolved.

Fig. 3 is a view showing in side elevation the knotter shown in the preceding views, 55 with the parts of the knotter in the position shown in Fig. 1.

Fig. 4 is a fragmentary vertical sectional view taken on the line 4-4 of Fig. 2.

Fig. 5 is a horizontal sectional view taken on the line 5-5 of Fig. 4.

Fig. 6 is a vertical sectional view taken on the line 6-6 of Fig. 5.

Similar reference characters refer to similar parts in each of the several views.

Referring specifically to the drawings and 65 particularly to Fig. 3, S designates an operating shaft to which is fixed for rotation therewith an upper disk D, a lower disk D', and a stationary disk D² loosely embracing the shaft and interposed between the movable disks. C designates a collar which is 70 slidably fitted upon the shaft S and urged upwardly in the direction of the disk D' by means of a coil spring R. The collar C bears against a plate P supported for vertical movement upon the disk D' by a pin N.

The knotter as thus far described is similar in construction to the knotter embodied in my pending application heretofore referred to so that a showing of the means for 80 rotating the shaft S to effect an actuation of the knotter, as well as the means for securing the disks D and D' to the shaft, is believed to be unnecessary.

The upper disk D is provided with a wire receiving slot designated at 15 which communicates at its inner end with a positioning recess 16 formed in the upper end of the shaft S. The left end wall of the slot 15 is provided with a projection 15^a for a purpose which will be hereinafter described. The lower or inner side of the disk D is 90 formed with a recess 16^a which, as clearly shown in Fig. 4, communicates at one end 95 with the slot 15. This recess 16^a is of a predetermined depth so as to accommodate wires of predetermined gage.

The stationary disk D² is also provided with a slot 17 which is of the form shown in 100 Fig. 5. The lower edge of the right hand wall of the slot 17 is formed to provide a cutting edge 17^a, which as shown in Fig. 4 is adapted to coöperate with a cutting edge 18^a formed on the left hand wall of a slot 18 formed in the lower movable disk D'. As shown in Fig. 5, the confronting sides of the slots 17 and 18 are formed with reversely curved edges so as to effect a shearing action 110 between the cutting edges 17^a and 18^a when the disk D' is rotated with respect to the disk D². As shown in Figs. 5 and 6, the

upper side of the disk D² is formed with a shallow recess 19 at a point adjacent to the slot 17. This recess 19 is adapted to effect a release of the ends of a loop of wire subsequent to the twisting operation as will be hereinafter described.

In operation, the three disks of the knotter normally occupy the position shown in Figs. 1 and 3, in which position the slots 15, 16, 10 17 and 18 are in registry to permit of the insertion of the ends of a loop of wire into the knotter and the insertion or threading of one of the wire ends between the lower movable disk D' and the plate P. When the 15 shaft S rotates to effect the rotation of the disks D and D' in the direction of the recess, the projections 15^a engage the wire ends and thus force the same into engagement with the upper edge of the right hand wall of the slot 20 17 thereby causing a right angular bending of the wires into the recess 16^a, it being understood that, as previously described, the disk D² is stationary. As previously explained, the recess 16^a is of a depth to accommodate wires of predetermined gage so that when they have been inserted into the recess, further movement of the disk D will cause the recess to be completely disaligned as with respect to the slot 17 causing a coaction 30 between the confronting faces of the disks D and D², to securely grip the wires therebetween.

As the lower movable disk D' moves with the upper disk D, it will be clear that after 35 the bending of the wire ends has been effected by the projection 15^a, the cutting edges 17^a and 18^a engage the wire ends and thus sever the latter. It is to be particularly noted that this cutting operation occurs subsequent to 40 the bending operation so that the angular bent portions of the wire ends are automatically moved into the recess 16^a upon continued movement of the disk D.

With the angular bent wire ends disposed 45 within the recess 16^a, continued rotation of the disk D causes a twisting of the wires in a manner which will be readily understood. When the twisting operation has been completed, the angular bent ends of the wire ends move into the recess 19, and because of 50 the contour of the latter it will be clear that when a pull is exerted upon the wire ends they will be readily removed from between the disks D and D² and in such manner as to 55 permit of the wire ends retaining their angular positions. This retention of the angular bent ends of the wire ends serves to maintain the wire ends in twisted position.

The automatic threading or insertion of 60 the wire supply end between the disk D' and the plate P will be readily understood from a consideration of the description and operation of the knotter embodied in the aforesaid pending application.

65 From the foregoing operation, it will be

clear that the bending and gripping of the wire ends occurs prior to the cutting operation thereby eliminating the danger of the severed wire ends slipping out of the knotter and thus permitting of the successful twisting of the ends. It will also be clear that as the recess 16^a is cut to a depth having a certain fixed relation with the diameter of the particular wire used, a gripping of the wire ends will be effective without the employment of the lug. This allows the cost of manufacture to be decreased to an appreciable degree as with the present construction it is only necessary to turn the recess out on a lathe while when the lug was used it was necessary to chisel out the recess adjacent the lug.

70 Although I have herein shown and described only one form of knotter embodying my invention, it is to be understood that 75 various changes and modifications may be made herein without departing from the spirit of the invention and the spirit and scope of the appended claims.

80 What I claim is:

1. A knotter comprising, a stationary member and a movable member, means carried by the movable member and co-operating with the confronting face of the stationary member for receiving the two ends of a 95 wire, bending and gripping the same between the members so that they will move with the movable member to effect a twisting of the wire and an ultimate releasing thereof in a manner to maintain the ends bent. 90

100 2. A knotter comprising, a stationary member and a movable member, means carried by said members for receiving the two ends of a wire, bending and twisting the same between the members so that they will move with the movable member to effect a twisting of the wire ends with an ultimate releasing thereof in a manner to maintain the ends bent, and a second movable member associated with the stationary member to 105 effect a cutting of the wire ends subsequent to the gripping operation.

110 3. A knotter comprising, a stationary member and a movable member, means carried by said members for receiving the two 115 ends of a wire, bending and twisting the same between the members so that they will move with the movable member to effect a twisting of the wire ends with an ultimate releasing thereof, and a second movable 120 member associated with the stationary member to effect a cutting of the wire ends subsequent to the gripping operation.

125 4. A knotter comprising, a stationary member and a movable member, means carried by said members for receiving the two ends of the wire, bending and twisting the same between the members so that they will move with the movable member to effect a twisting of the wire ends with an ultimate 130

releasing thereof, a second movable member associated with the stationary member to effect a cutting of the wire ends subsequent to the gripping operation, and a plate urged 5 toward one of the movable members and co-acting therewith to frictionally hold one of the cut ends of the wire within the knotter when said movable member is moved.

5. A knotter comprising, a pair of movable members, a stationary member between the movable members, means for rotating the movable members, all of the members being formed with wire end receiving slots with certain of the walls of certain of the slots 10 coacting to effect a bending of the wire ends, and other walls of the slots coacting to effect a cutting of the wire ends subsequent to the bending operation, a recess formed in one of the movable members to receive the 15 bent ends and to cause the stationary member to coact with the said movable member to grip and twist the wire ends, and a recess 20 formed in the stationary member to effect a release of the wire ends subsequent to the twisting operation in a manner to maintain the wire ends bent.

formed in the stationary member to effect a release of the wire ends subsequent to the twisting operation.

25

6. A knotter comprising, a pair of movable members, a stationary member between the movable members, means for rotating the movable members, all of the members being formed with wire end receiving slots with certain of the walls of certain of the slots 30 coacting to effect a bending of the wire ends, and other walls of the slots coacting to effect a cutting of the wire ends subsequent to the bending operation, a recess formed in one of the movable members to receive the 35 bent ends and to cause the stationary member to coact with the said movable member to grip and twist the wire ends, and a recess formed in the stationary member to effect a release of the wire ends subsequent to the 40 twisting operation in a manner to maintain the wire ends bent.

ALBERT EARL CRANSTON.
